UNITED STATES PATENT OFFICE.

CLIFTON CHISHOLM, OF CLEVELAND, OHIO, ASSIGNOR TO THE AMERICAN MULTIGRAPH COMPANY, OF CLEVELAND, OHIO, A CORPORATION OF OHIO.

ADDRESSING MACHINE.

Application filed July 11, 1924. Serial No. 725,370.

To all whom it may concern:

Be it known that I, CLIFTON CHISHOLM, a citizen of the United States, residing at Cleveland, in the county of Cuyahoga and State of Ohio, have invented a certain new and useful Improvement in an Addressing Machine, of which the following is a full, clear, and exact description, reference being had to the accompanying drawings.

10 The object of this invention is to provide in a very simple manner an addressing machine adapted for use indiscriminately with address plates of different thickness. One addressing system on the market provides 15 metal plates, each embossed with a plurality of lines, such plate mounted as a unit on a suitable holding plate. Another addressing system provides a holder having rows of upstanding overhanging buttons, connected 20 by narrower upwardly formed corrugations and embossed strips, each having a single line of characters, and each resting on the top of a row of buttons and corrugations and retained in place by flanged edges which 25 extend beneath the projections of the buttons. This latter address plate has a greater overall thickness than the address plate of the first mentioned system.

The addressing machine of the present invention is designed to print from either of these types of plate indiscriminately, so that no harm results if either type of plate becomes mixed with the others. In fact, my addressing machine enables the use of the 35 single embossed plate, where the relation of the name and address is never changed, in conjunction with the individual line embossed strips which enables a ready change of the name or any portion of the address.

40 In accomplishing the above described results, I provide a bed member which receives the thrust of the platen against the interposed paper and plate in such form that without changes it may support the 45 thinner address plate with its bottom at a correspondingly higher elevation than the thicker plate. In the particular instance of the address plates mentioned, I provide a bed with parallel upstanding ribs, the tops 50 of which may engage the flat bottom of the thinner address plate, and hold it at proper printing height or may enter the grooves formed in the underside of the thicker address plate by reason of the upstanding corrugations thereof and thus hold such ad-

dress plate at the same printing height. Accordingly, no adjustment of the platen stroke is required for the different address plates, and they may be fed one after another across the bed and caused to impress 60 the paper without regard to which type of address plate is acting.

I am using the term "address-plate" herein as covering the composite structure, comprising a holding plate and a member or 65 members mounted thereon and having printing faces for a name and address or equivalent matter.

70 My invention is hereinafter more fully explained in connection with the drawings 70 which illustrate that portion of the machine with which the present invention is concerned. Such features are hereinafter more fully explained in the detailed description 75 of the embodiment shown in these drawings.

75 In the drawings, Fig. 1 is a plan of a portion of an addressing machine equipped with my invention, this view showing each 80 of two characters of address plates on the conveyor. Fig. 2 is a sectional side elevation of such portion of the addressing machine showing also the platen and a portion of its operating arm. Fig. 3 is a perspective view of the address plate bed, made 85 in accordance with this invention, this view showing also a portion of the holder plate of the thicker type of address plate. Fig. 4 is a diagrammatic view showing in end elevation, the supporting bed, the left hand half 90 of the view showing such bed with the thinner plate thereon, and the right hand half with the thicker plate thereon.

95 As shown in the drawings, 10 indicates the plate-supporting bed of the machine having parallel upstanding ribs 11. A suitable support 12 is shown as extending at a lower elevation from the ribbed bed. A pair 100 of conveyor chains 15, shown as propelled by sprocket wheels 16, travels along the opposite sides of the bed and extension for conveying the address plates from a suitable supply (not shown) to the ribbed bed. The sprocket chains have upstanding projections 105 17 arranged at intervals and adapted to engage the address plates and shove them forwardly; that is, toward the left in Figs. 1 and 2. 20 designates the platen above the ribbed bed, which is shown as carried by an operating arm 21 in the usual manner. 110

The so-called thinner address plate is shown at A in Figs. 1, 2 and 4 and the thicker address plate at B in the same figures. The thin address plate is shown as comprising a sheet of metal a , having an upwardly and inwardly curled edge flange a^1 and turned up tongues a^2 , curled toward the flange a^1 . A plate a^3 embossed with several rows of characters is slid into place between the flange a^1 and the tongues a^2 . The total thickness of this address plate, it will be seen, comprises the thickness of the plate a , of the plate a^3 and the amount by which character faces are raised above the latter plate.

The thicker address plate B comprises a holder plate b having upstanding corrugations b^1 extending parallel with each other across the plate and upstanding buttons b^2 in the row of corrugations, with their top surface in the line of the ridge of the corrugations but extending laterally therefrom in a plane parallel with that of the body of the plate, so as to provide overhanging edges b^3 free from the body of the plate. The embossed strips designated b^3 have upwardly embossed characters on their faces and flanges at their edges adapted to extend beneath the arcuate edges of the buttons when the strips lie on the tops of the corrugations and buttons.

It will be seen that in the case of this B type of address plate the total thickness consists of the thickness of the holder plate b , the thickness of the embossed strip, the amount the characters project above the top of the strip, and in addition to these thicknesses, the amount which the corrugations rise above the top surface of the plate B. Accordingly, this plate B is thicker than the address plate A. The amount by which it exceeds in thickness would correspond to the height of the corrugations (i. e. the depth of the groove on the underside of the plate B) if the other factors were equal, but in practice the amount by which the characters are raised above the plate a^3 differs from the projection of the characters on the strip b^3 . Also the plate a^3 may be of different thickness from the strip b^3 , and likewise the plates a and b may differ in thickness.

The ribs 11 on the bed are located a distance apart corresponding to that of the corrugations on the address plate B. The height of these ribs corresponds to the difference in overall thickness between the two types of address plates. It therefore follows that when the thin address plate of the A-type comes over the bed, it is supported by the tops of the ribs at a definite height, as shown in the left hand portion of Fig. 4, whereas, when an address plate of the B type comes into registration with this bed it drops down so that the body of the plate extends between the ribs 11 and the bottom

rests on the bed proper while the sides of the corrugations straddle the ribs. The result is that the printing face is in the same horizontal plane as that of the printing face on the A type of address plate.

It will be understood from the description given that address plates of the A and B types may be placed indiscriminately in the magazine for the machine and fed by the conveyor to the bed and platen and printed form, without regard to the character of plate, by a platen having constant stroke.

I have indicated in Fig. 2, a sheet of paper P in position to be printed, and an inking machine R for effecting the inking. It is to be understood, however, that the printing surfaces may be inked in other manner if desired.

Having thus described my invention, I claim:

1. In an addressing machine, the combination, with address plates of different thicknesses, of means for feeding them indiscriminately, and means adapted to support such plates at a constant face elevation.

2. In an addressing machine, the combination, with address plates of different thickness, of a bed adapted without adjustment to support such plates at a constant elevation.

3. In an addressing machine, the combination with different types of address plates of a platen, and a bed having projections extending toward the platen and adapted to support such different types of address plates with the printing surface in the same relation to the platen.

4. The combination with two kinds of address plates, one of which has a flat bottom, and the other a grooved bottom, of an addressing machine having means provided with projections adapted to support the flat bottom plate with its lower surfaces in the plane of the top of the projections and adapted to support the grooved plate with the projections occupying the grooves.

5. In an addressing machine, the combination of a bed having parallel ribs, a platen adapted to coat therewith, and means for conveying address plates into position between the ribs and platen, whereby grooved and ungrooved plates of relatively different thickness may be supported with their faces in the same printing plane.

6. In an addressing machine, the combination of a bed having projections, relatively thin address plates adapted to rest against the face of the projections and thicker address plates adapted to rest against the bed between projections.

7. In an addressing machine, the combination of a bed having parallel upstanding ribs thereon, a platen above the bed, relatively thin plates adapted to stand on the

- ribs, and relatively thick plates having grooves into which the ribs may extend, while the bottom of the plates rest on the bed between the ribs.
5. 8. In an addressing machine, a bed having parallel upstanding ribs thereon, a conveyor adapted to carry address plates one after the other into position over bed, and a platen adapted to coact with a plate when 10 on such bed, in combination with two kinds of address plates, one adapted to rest on top of the ribs and the other to depend between them.
9. The combination with a relatively thin 15 address plate and a relatively thicker address plate having a grooved bottom, of a machine having a supporting member for the plate, said supporting member having projections of a height corresponding to the 20 difference in thickness between the two types of plates.
10. The combination with an address plate having a substantially flat bottom and another address plate having a bottom with 25 parallel grooves therein, a platen, and a supporting bed coacting with the platen and having upstanding ribs spaced in correspondence with the grooves and having a height equal to the amount by which the 30 thickness of the flat bottom address plate exceeds the thickness of the grooved bottom address plate.
11. In an addressing machine, the combination with a platen of a coacting member 35 having parallel equidistant ribs on its face, whereby comparatively thin plates may have their bottoms engage the top of the ribs and thicker grooved plates may occupy space between the ribs and thus both plates 40 present their impression faces in the same plane.
12. The combination with an address plate having a flat bottom and an embossed sheet of metal secured thereon and another address plate having upwardly bent corrugations and lateral projections at the top of the corrugations and embossed strips overlying the corrugations and projections, and a member to receive the printing thrust and 45 having parallel projecting ribs arranged on a distance apart corresponding to distance 50
- between corrugations and having a height equivalent to the difference in thickness between the flat bottom address plate and the corrugated address plate.
13. The combination with a plurality of address plates some of which are of one thickness, and others of a greater thickness, of an addressing machine having a member 55 to receive the printing thrust, which member is adapted to support the address plates with their bottoms at different elevations according to the thickness of the plates, whereby the acting faces of the address plates are at the same elevation irrespective 60 of their thickness.
14. In an addressing machine, the combination of a bed having parallel upstanding ribs thereon, a platen above the bed, relatively thin plates adapted to stand on the 65 ribs, relatively thick plates having grooves into which the ribs may extend, and a pair of conveyor chains having projections adapted to convey either type of plate indiscriminately into position between the bed and 70 platen.
15. An addressing machine, the combination of a bed having parallel upstanding ribs thereon, a platen above the bed, a pair of conveyor chains adapted to convey plates 75 into position between the bed and platen, whereby plates of different thickness may be indiscriminately used, and inking means suitable for either type of plate.
16. The combination with address plate 80 having a flat bottom and an embossed sheet of metal secured thereon, another address plate having upwardly bent corrugations and embossed strips overlying the corrugations and resting thereon, a bed having parallel projecting ribs arranged a distance apart, corresponding to distance between 85 corrugations and having a height equivalent to the difference in thickness between the two types of address plates, conveyor chains 90 for feeding the two types of plates indiscriminately, means for inking either type of plate, and a platen adapted to coact with either type of plate when on the bed.
- In testimony whereof, I hereunto affix my 95 signature.

CLIFTON CHISHOLM.
